G. O. CASE.
REINFORCED CONCRETE GROIN.
APPLICATION FILED SEPT. 18, 1915.

Patented Mar. 28, 1916.

UNITED STATES PATENT OFFICE.

GERALD OTLEY CASE, OF NEW YORK, N. Y., ASSIGNOR TO CASE COAST PROTECTION CORPORATION, OF NEW YORK, N. Y., A CORPORATION OF NEW YORK.

REINFORCED CONCRETE GROIN.

1,177,381.

Specification of Letters Patent. Patented Mar. 28, 1916.

Application filed September 18, 1915. Serial No. 51,380.

To all whom it may concern:

Be it known that I, GERALD O. CASE, a subject of the King of Great Britain, and a resident of the city of New York, borough 5 of Manhattan, in the county and State of New York, have invented a new and Improved Reinforced Concrete Groin, of which the following is a full, clear, and exact description.

10 This invention relates to reinforced concrete groins or the like adapted for erection along the shores of lakes, rivers or seas, and has particular reference to means adapting such groins to be erected in sections applied one to another without requirement for special machinery or driving of piles or the like.

Among the objects of the invention, therefore, is to provide a means for erecting a 20 shore groin from an assemblage of similar units, each of which is adapted to be self-supporting and self-locking in practice and which may be put in place with facility either above or below the surface of the 25 water.

With the foregoing and other objects in view, but without limiting the invention to the specific construction illustrated, the 30 novelty resides in the general arrangement and combination of parts hereinafter more fully set forth and claimed and illustrated in the accompanying drawings in which—

Figure 1 is a side elevation, partly in longitudinal section, of a preferred form 35 of the invention; Fig. 2 is a plan view of the same; Figs. 3 and 4 are plan views of modified forms of the improvement; and Fig. 5 is a transverse sectional detail on the line 5—5 of Fig. 2.

40 Referring more particularly to the drawings, I show a series of connected box-like elements 10 adapted to be arranged end to end and extend from the bank or shore line outwardly to any desired distance in a vertical plane substantially perpendicular to the shore line.

Each of the boxes 10 comprises side members 11 parallel to each other, end members 12 which, in the preferred form, are also 50 parallel but inclined with respect to the vertical, and a substantially horizontal bottom 13 arranged between the top and the bottom edges of the box.

The box is preferably made of reinforced 55 concrete, though as to the material I do not

wish to be unnecessarily limited. Suffice it to say, however, that it is made of a strong, substantial structure, and of sufficient weight to sink automatically into the water and into the bed of the body of water as, 60 for instance, into the sand indicated at S. The side members 11 at the sea end of the box project somewhat beyond the sea end wall 12 and thereby, in connection with the adjacent end wall, constitute a seat for the 65 adjacent land end of the next adjacent box. The corners formed by the acute angularly shaped lower ends of the box are in the nature of spurs, projecting into the bed of the body of water, thereby tending to lock 70 the box in fixed position. From what has been set forth, it will be apparent that each box is adapted to settle automatically until it rests substantially upon the body of sand or the like and yet it is possible for any 75 one of the boxes to be removed or replaced, if desired, without disturbing any other elements of the groin. At the land end of the groin is provided a foundation member 14 which may be anchored in position by 80 means of piles 15 or other suitable structures, the same being provided with outwardly projecting flanges and an adjacent wall 17 adapted to receive the land end of the first standard element 10 in the manner 85 already set forth.

Any of the elements, either the foundation member 14 or box element 10 may serve to support post-like uprights 18 having 90 grooves 19 adapted to receive longitudinal planks or panels 20 for the purpose of building up the height of the groin as occasion may require.

A groin may be erected, by the use of the means herein set forth, either above or below the surface of the water. In other words, the operation may continue at high tide as well as low. The nature of each box is such that it may be floated over the place of deposit and there allowed to sink by filling with water through any one or more holes 21 formed in the bottom. Obviously these holes may be plugged up temporarily for the purpose of floating the device over the site therefor. When the device is filling 105 with water, it is obvious that it may be guided and held to its proper position with a minimum amount of effort, the land end of each device being guided by the sea end of the next preceding element, and the spur 110

outer ends thereof will settle and hold the device in place. When the elements are thus settled into permanent position, they readily become filled with sand or the like 5 deposited therein by the action of the water and are thereby ballasted in such a manner as to become a permanent fixture. The box structures may be provided with any suitable number of transverse tie bars 22 extending from the top of one side 11 to the top of the other side for the purpose of stiffening and reinforcing the same.

As suggested in Figs. 3 and 4, the engaging 15 ends of adjacent boxes may be interlocked so as to prevent endwise as well as lateral displacement, but still permitting any one of the elements to be lifted so as to be replaced by another, if desired. As shown in Fig. 3, one end of each section is provided 20 with a tongue 23 coöperating with a dove-tail groove 24 in the next adjacent element, the tongue being formed at the outer or sea end of each element. In Fig. 4, however, either end of each element may be provided 25 with an undercut or dove-tail channel 25 into which is slidably fitted the enlarged end 26 of the next adjacent element. These detail Figs. 3 and 4, are intended to set forth the fact that any desired means for locking 30 the adjacent elements may be resorted to, and it is obvious that the additional features, such as the uprights 18, cross ties 22, and the like, may be employed in connection therewith as well as in the structure 35 shown in Figs. 1 and 2.

The posts or uprights 18 are preferably made separate from the main portions of the groin and are adapted to coöperate with one or the other of the side walls 11 as indicated in Fig. 5, each post having a lip 27 lapping over the outside of the wall 11 and having a leg on the inside terminating in a foot 28 projecting into a hole 21 whereby the post is locked in position. The trans- 45 verse bars 22 may be located at any desired place, but as indicated in Fig. 2 they may be arranged to brace the posts, preventing

movement thereof lengthwise of the groin in addition to the interlocking connection between the foot 28 and the hole 21.

50

I claim:

1. The herein described concrete groin structure element comprising a box-like device having side and end walls and an integral bottom arranged intermediate the top and bottom edges of the side and end walls, the element being adapted to settle into the shore or sea bed substantially up to said bottom whereby it is automatically locked by means of the said side and end walls in position.

55

2. The herein described concrete groin element comprising a box-like structure adapted to float over the place of deposit and comprising parallel side walls, parallel inclined end walls, the side walls projecting beyond one end wall forming a channel for the next adjacent element, and a bottom panel arranged intermediate the top and bottom edges of the side walls, said bottom being provided with a hole therethrough adapted to be plugged temporarily for floating and removable for permitting the filling thereof with water to permit the device to settle and embed itself automatically into the shore or sea bed substantially to the bottom panel, the end walls being inclined toward the land.

60

3. In a reinforced concrete groin, the combination of a plurality of interlocking box-like elements adapted to anchor into the shore or sea bed, each element having a transverse floor with a hole therein, a series of posts adapted to be attached to the elements, each post being so formed as to straddle one side wall of an element and having means interlocking with said bottom hole, and a series of planks extending between the several post elements.
